(57) **CLAIM**

The ornamental design for a display screen with animated graphical user interface, as shown and described.

DESCRIPTION

FIG. 1 is a front view of an electronic device having a display screen with an animated graphical user interface applied to the display screen and showing a first image of the claimed design;

FIG. 2 is a second image thereof;

FIG. 3 is a third image thereof;

FIG. 4 is a fourth image thereof;

FIG. 5 is a side elevation view thereof, the opposite side elevation view being a mirror image thereof;

FIG. 6 is a top plan view thereof, the bottom plan view being a mirror image thereof;

FIG. 7 is a rear elevation view thereof;

FIG. 8 is a front view of an electronic device having a display screen with an animated graphical user interface applied to the display screen and showing a first image of a second embodiment of the new design;

FIG. 9 is a second image thereof;

FIG. 10 is a third image thereof;

FIG. 11 is a fourth image thereof;

FIG. 12 is a side elevation view thereof, the opposite side elevation view being a mirror image thereof;

FIG. 13 is a top plan view thereof, the bottom plan view being a mirror image thereof; and,

FIG. 14 is a rear elevation view thereof.

The evenly spaced broken lines in the drawings show an electronic device, a display screen or portion thereof with graphical user interface elements, a charging device that form no part of the claimed design. The dot-dash broken lines in the drawings show a display screen and form no part of the claimed design.

The appearance of the animated image sequentially transitions between the views shown in FIGS. 1-4 and FIGS. 8-11, respectively. The process or period in which an image transitions to another forms no part of the claimed design.
